UNITED STATES PATENT OFFICE.

WILLIAM H. BLANCHARD, OF GAINESVILLE, GEORGIA.

MACHINE FOR FILING COTTON-GIN SAWS.

SPECIFICATION forming part of Letters Patent No. 338,025, dated March 16, 1886.

Application filed July 24, 1885. Serial No. 172,543. (No model.)

To all whom it may concern:

Be it known that I, WILLIAM H. BLANCHARD, a citizen of the United States, residing at Gainesville, in the county of Hill and State of Georgia, have invented certain new and useful Improvements in Machines for Filing Cotton-Gin and Linter Saws; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

My invention relates to mechanism designed for forming needle-pointed teeth on gin and linter saws; and it consists in certain improvements on a machine for this purpose patented by me on the 10th day of July, 1883, No. 280,900.

Referring to the accompanying drawings, Figure 1 is a plan of my machine with portions removed or broken away. Fig. 2 is a side view, and Fig. 3 a top view, of a cheek-piece and a portion of a rest-bar, showing the manner of making the rest-bar adjustable in the cheek-pieces. Fig. 4 is a front view, and Fig. 5 a side view, of a portion of the feed-bar provided with three bits, one of the side bits in Fig. 5 being thrown up out of working position. Fig. 6 represents the file-holder.

Similar letters of reference refer to like parts in all the figures.

The frame-work of the machine consists of a rear upright and rectangular end piece, *a*, to which are secured by bolts horizontal side rails, *b b*, which are united at the front by an integral cross plate or rail, *c*.

A represents the main or crank shaft of the machine, and it is provided with a crank, *a'*, and rotates in bearings *a²*, fixed to the side rails, *b b*. At the center of the shaft *A* is a fixed master - gear, *A'*, which meshes with a pinion, *B*, fixed to a short counter-shaft, *C*, mounted in brackets *c'*, formed upon or secured to the rear end piece, *a*.

Upon the ends of counter-shaft *C* are fixed disks *C'*, to which connecting-rods *D D'* are attached by ordinary adjustable wrist-pins, *c²*, the heads *d'* of which are pivoted to the said

rods. The rod *D* is pivotally connected to a similar head, *d'*, at its front end, which head is pivotally connected by a bolt or screw, *d³*, to a cross-head, *E*, located above the horizontal center of the machine, while rod *D'* is in like manner connected and arranged with reference to a second cross-head, *E'*, extended below said center of the machine, the construction of the parts in each being as follows: Each of the cross-heads slides upon guides *E²*, supported at their rear ends upon studs *F*, secured by set-screws *f'* in sockets formed upon the side rails, *b*, having slotted inwardly-projecting curved arms *f*, and at their front ends said guides rest against the upper and lower surfaces, respectively, of the cross-bar *c* of the frame-work, which is slotted at *c² c³*; for the passage therethrough of bolts *f² f³*, which bind said front ends of the guides *E²* to links *G G*, the outer ends of which are connected by a pin or bolt, *g*, passing through a slot, *c⁴*, in cross-bar *c*. One of the links *G* is provided with a projecting arm, *G'*, constituting with the link a bell-crank, which is connected by a rod, *G²*, with bar *G³*, supported upon the inside of the bearing *a²* and in the rear frame-piece, *a*, and provided with an inwardly-projecting lug, *g'*, said bar *G³* being operated by a wrist-pin, *h*, in a disk, *H*, secured to the main shaft *A*. The rear ends of the guide are adjustably secured in the slots of the arms *f* of the studs *F*. Springs *I I* rest at their ends against the rear side of arms *f*, and are curved to conform thereto, and are extended to the front, where they rest one upon each of the guides *E²* and against its edge. Screws *i i* serve to vary the tension of the springs.

Each of the cross-heads is connected to a file-holder, *J*, shouldered at its rear end, to fit a bearing for the same formed in the cross-head, and of cylindrical form in cross-section, to fit suitable bearings, *E³*, therefor formed in the front ends of the guides. Each of the holders is exteriorly grooved, as at *j*, and in each of the bearings *E³* is a screw (not shown) which projects into the groove *j*, for giving proper motion to the holder at each stroke. A set-screw, *j'*, serves to secure the shank of the file *K* within the holder. The files are diamond shape in cross-section, and are presented to the saw so that one of the sides of

the file is brought into contact with the teeth of the saw.

M represents a yoke, the rear ends of which are fitted in bearings formed on the rear frame, 5 a, and inclose coil-springs (not shown) which encircle said yoke ends and act to draw the yoke rearwardly, while lugs m' m' thereon, when acted upon by projecting wrist-pins or lugs m² m², formed on the master-gear A', act to press 10 the yoke forward.

The above description embraces so much of the construction covered in my patent above mentioned as is necessary to show the relation thereto of my improvements on that machine, 15 and it is to be understood that anything shown in said patent and herein described is not claimed in this application.

I will now proceed to describe the improvements.

20 In order to support the front end of the machine, (the rear end being supported by the rear end piece, a,) I secure to the side rails, b b, cheek-pieces d d, which are clamped to the rails by means of a clamp-screw, d⁴. 25 At their front ends these cheek-pieces are recessed, as shown at d⁵ in Fig. 2, and between the recessed ends of the cheek-pieces, on each side of the frame, is placed the rear end of a rest-bar, e, which, for lack of space, are shown 30 broken off, but which are designed to be extended, and when the machine is in use rested upon the shaft or arbor of the saw or saws being operated upon. The rear end of each rest-bar is pivoted in the cheek-pieces by a headed bolt, e', passing from the outside through said pieces and through the bar, and engaging with a nut, e'', on the inner side, as clearly shown in Fig. 3.

For the purpose of making the rest-bars adjustable vertically to suit different kinds and sizes of saws and gins and to change the pitch of the files on the saws, I provide the front ends of the cheek-pieces with adjusting-screws k k, one above and the other below the rest-bar, 45 and these screws are provided with jam-nuts l l, to aid in holding the bar firmly in position. It will thus be seen that bolt e' serves as a pivot for the bar, which can be adjusted up or down within a reasonable limit by the 50 screws k k.

A feed-bar, N, is pivotally secured to the front end of yoke M, and extends forward to the saw, (not shown,) where it is provided with side tongues, n', by which it is kept in line with and upon the saw. Instead, however, of the bar being provided with a single bit, as in my before-mentioned machine, it carries three bits, by which means I am enabled to feed one, two, or three saws at the same 55 time. This is an important feature, a defect in the machine alluded to being that in case the bit came to a broken tooth it would not feed over, and the files would then dwell in one place and make an ugly notch in the saw. 60 Now, if I have a saw to operate upon which has broken teeth, by placing another along-

side of it on the arbor, or one on each side of it, a sure feed is obtained by means of the side bit or bits. The two side bits, o', are pivoted to the feed-bar by a bolt, o'', and are limited in 70 their downward movement by a bolt, s, passing through the feed-bar, but are capable of being thrown up out of working position, as shown in Fig. 5. The center bit, o, is shaped at its inner end to fit a recess, s', in the end 75 of the feed-bar, and it is adjustably secured to said bar by a screw-bolt, t, passing through a steel plate, t', and through a slot in the bit, and thence into the bar, as may be seen in Figs. 4 and 5. By making this bit adjustable 80 in a lengthwise direction I am enabled to compensate for the wear of the bit. The center bit is wholly of steel, and the side bits may be of brass or like material, with a steel point secured thereto. 85

The file-holder in use in my above-mentioned machine is objectionable, in that it is so formed as to give the file a twist all one way as it goes forward, whereby either the top or bottom of the teeth is improperly acted 90 upon. It will be seen on reference to Fig. 6 that I now form the groove j spirally in one direction, then straight, and, finally, spirally in the opposite direction, so that the file starts off on a twist for one-third the stroke, then 95 runs straight for a like distance, and then reverses the twist, perfectly rounding the tooth at both top and bottom.

With the exception of what has been herein stated as to the operation of certain parts, 100 the general operation of the machine is the same as that described in my Patent No. 280,900, before mentioned, and therefore need not be herein described.

Having thus fully set forth my invention, 105 what I claim as new, and desire to secure by Letters Patent, is—

1. In a saw gumming and filing machine, the combination, with cheek-pieces attached to the side rails of the machine, of vertically adjustable rest-bars for supporting the front 110 of the machine in proper relation to the saw, substantially as described.

2. In a saw gumming and filing machine, the combination, with cheek-pieces removably secured to the side rails of the machine, of vertically-adjustable rest-bars pivoted at their rear ends in the cheek-pieces and governed in their upward and downward adjustments by adjusting-screws in the ends of the 120 cheek-pieces, substantially as described.

3. The combination, with the feed-bar, of a longitudinally-adjustable center bit secured to the bar by a screw or bolt, and two side bits pivoted to the bar, said side bits, when in working position, resting on the ends of a rod passing through the head of the feed-bar, substantially as described. 125

4. The combination of the file-holder, formed with a groove spiral in one direction, straight 130 for a like distance, and then spiral in an opposite direction, with a screw fixed in a suit-

able part of the machine, for giving the file a
twist in one direction for one-third of the
stroke, then a straight movement for a like
distance, and, finally, another twist in an op-
5 posite direction, thereby rounding the tooth
both at top and bottom, substantially as set
forth.

In testimony whereof I affix my signature in
presence of two witnesses.

WILLIAM H. BLANCHARD.
